UNITED STATES PATENT OFFICE

EMANUEL J. PERRY, OF NEW BEDFORD, MASSACHUSETTS, ASSIGNOR, BY MESNE ASSIGNMENTS, TO THE AMERICAN LAUNDRY MACHINERY COMPANY, OF NORWOOD, OHIO, A CORPORATION OF OHIO.

AUTOMATIC WASHING MACHINE

Application filed November 28, 1927. Serial No. 236,255.

This invention relates to laundry machines and more particularly to the commercial or industrial type of washing machine.

In commercial or industrial laundry plants, a considerable number of large washing machines are employed as a part of the equipment for carrying out laundry operation. Cylinder machines of the fixed cylinder type or of the automatic unloading type are customarily employed in plants of this character. These machines are designed to permit the treating of material according to a wide variety of washing formulæ involving the use of hot and cold water, bleaching, bleach, sour, soap, and the like substances. These formulæ differ as to the ingredients employed, the sequence in which they should be introduced and the duration of the introduction of the several ingredients, according to the character and condition of material to be treated. It is apparent, therefore, that in a plant of this character, each machine requires a certain amount of attention of a skilled operator, and, due to the natural limitations on human accuracy and speed, a number of such operators may be required for the care of a large number of machines. Moreover, the production of a uniform class of work requires a degree of skill on the part of the operator which is often lacking and which at best is unreliable. Knowledge of these circumstances has resulted in attempts to produce a machine capable of carrying out certain washing cycles in a substantially automatic manner, but such machines do not possess the simplicity of construction, the flexibility of adjustment to accommodate the desired variety of washing formulæ, or the degree of accuracy and dependability required of a commercial machine. My invention relates to the provision of an automatic commercial type of machine which fulfills this and other requirements.

It is an object of my invention to provide an automatic laundry machine capable of carrying out a complete cycle of washing operations without requiring the attention of an operator.

It is also an object of my invention to provide an improved form of automatic mecha-

nism for controlling and permitting the adjustment of the valve actuation which governs the washing formula.

A further object of my invention resides in the provision of a machine for automatically introducing predetermined quantities of washing fluids and which takes into account and compensates for any and all variations in pressure which might exist in the fluid supply mains.

My invention also embraces as an object, means for automatically actuating the outlet valve of the machine in any desired predetermined sequence with reference to the introduction of the several washing substances.

Another object of my invention relates to the provision of means whereby the operator or attendant can tell at a glance just what portion of a washing cycle the machine is performing at any given time.

Other objects and advantages of my invention reside in the structural details and refinements in a machine of the character indicated, all of which, together with the foregoing objects, will be hereinafter more clearly pointed out.

In the drawings,

Fig. 1 is a view in end elevation of a cylinder type of washing machine with my invention applied thereto,

Fig. 2 is a rear elevation of the entire machine and illustrating particularly my improved valve mechanism and its relation to the intake conduits of the cylinder.

Fig. 3 is a sectional view taken substantially on line 3-3 of Fig. 2 and illustrating the intermittent drive for my improved cam cylinder.

Fig. 4 is a longitudinal sectional view of the cam cylinder and its enclosing casing taken substantially on line 4-4 of Fig. 3.

Fig. 5 is a view in transverse section of the cam drum.

Fig. 6 is a detailed view illustrating one of the inlet valves together with its actuating solenoid.

Fig. 7 is a view similar to Fig. 6, but illustrating another of the inlet valves with which an auxiliary controlling mechanism is associated.

Fig. 8 is a development in plan of my improved cam cylinder and illustrating the disposition of the adjustable cams thereon according to an illustrative example of a washing formula.

Fig. 9 is a circuit diagram showing the arrangement of the solenoids, their controlling cam actuated switches, and the auxiliary manually operable switches.

10 In the drawings, I have shown my invention as applied to a washing machine of an automatic unloading cylinder type, but I desire it understood that this disclosure is used merely by way of illustration and that my invention may be applied with equal advantage to any type of laundry machine wherein it is desired to perform a series of operations in an automatic manner.

15 The washing machine is indicated generally by the reference character 1 and is provided with a conventional type of outlet valve 2 for discharging the washing fluids from the cylinder. Conduits 3 communicate with the cylinder at the rear side thereof and are connected by a common manifold 4 which in turn connects through a conduit 5 with a second manifold 6. Conduits for a plurality of sources of washing materials are indicated in Fig. 1 by the reference numeral 8 and as 20 illustrated in this figure and also in Fig. 2, these conduits open into valves 9 and 9a, which valves communicate with the second manifold 6 through their respective conduits 7 and 7a. Valves 9 are of the well known 25 commercial type and ordinarily embody an actuating handle 10 whereby communication may be had from any desired source of supply through a selected conduit 8, valve 9, or 30 9a, conduits 7 or 7a, manifold 6, conduit 5, and manifold 4 leading to the cylinder. It is apparent that with the mechanism thus far described, any desired washing cycle may be carried out by suitable manual manipulation of the several valves 9 and 9a and of 35 the outlet valve 2. This structure corresponds in a general way to the machines commonly employed in commercial or industrial laundry plants.

40 My invention relates partly to a mechanism for automatically actuating the several valves 9 and 9a and the outlet valve 2 in any desired predetermined sequence and to so operate any of such valves for any desired predetermined period. To this end, I have provided a solenoid 12 for each of the said 45 valves 9, a solenoid 12a for each of the said valves 9a, and an additional solenoid 12b for actuating the outlet valve 2. As illustrated in Fig. 6, each solenoid 12 is connected by a link 11 with the lever 10 of the associated valve 9. It will also appear from Fig. 7 that the handles 10 of valves 9a are likewise connected by links 11a with solenoids 12a. Additional mechanism is provided in connec-

tion with valves 9a, the structure and purpose of which will be hereinafter described.

For energizing the several solenoids above mentioned, I have provided a plurality of switch elements, each embodying a stationary 70 contact member 28, a pivotally mounted contact member 27 having a roller carrying arm 26, and a second arm 29 for coaction with a spring member 30 whereby the pivoted contact member is normally maintained out of engagement with the stationary contact. One of these switch units is provided for each of the above mentioned solenoids, and an arm 26 of each pivotally mounted switch member is provided with a fiber or other suitable form of roller for coaction with my improved cam cylinder which will now be described. Referring particularly to Figs. 4 and 5 of the drawings, there is shown a cylinder 21 which is keyed or otherwise removably secured for rotation with a shaft 18 which is journaled at one end in the end wall of a casing member 31 and at its opposite end in a cross bar 34 which is hinged at one side to the casing. By virtue of this manner of mounting the drum, it is apparent that by swinging the strap or bar 34 laterally, the cylinder may be freely removed endwise from the housing for purposes of adjustment or substitution as will hereinafter appear. The periphery of the drum 21 is formed with a plurality of spaced annular channels 22 for the reception of cam elements 24. In order to adjustably secure the cam elements 24 in such channels, each channel is provided with a plurality of closely spaced apertures drilled therein radially of the axis of the cylinder. These apertures are threaded for the reception of securing bolts 25 which pass through the cam members 24 and have their heads received in countersunk openings in the cam surfaces. It will be appreciated that by the provision of this multiplicity of closely spaced apertures, it is possible to minutely adjust the cam elements 24 circumferentially 105 of the channels 22. It will be understood, of course, that the cam elements 24 are adapted to coact with the rollers carried by the pivotally mounted switch elements for periodically 110 opening and closing the contact between the elements 27 and 28 of the switch unit.

115 The usual transmission mechanism for rotating and elevating the cylinder in a machine of the type herein disclosed is housed within a casting 13 which additionally provides a 120 support for the operating motor 14. Located below the motor is a transmission shaft 15 which is journaled in these casting members 13 and which is in permanently geared 125 relation with the motor shaft. Suitable selective transmission mechanism is provided between the transmission shaft 15 and the cylinder rotating and cylinder elevating mechanism. The constantly rotating shaft 15 is utilized for imparting the desired motion to 130

the cam drum 21, this motion being preferably such as to effect a single rotation of the cam cylinder during a complete washing cycle of the machine. The motion transmitting connections employed for this purpose comprise a crank arm 16 secured for rotation with the transmission shaft 15 and connected by a link 17 with an oscillating arm 17' journaled on the shaft 18 of the cam drum. The 10 arm 17' carries a pawl 19 for coacting with the teeth of the ratchet wheel 20 which is secured to shaft 18. It will thus be seen that during rotation of the motor 14 and transmission shaft 15, an intermittent movement 15 will be imparted in one direction to the cam drum 21. As before stated, this transmitting mechanism is so designed as to produce one complete rotation of the cam drum during a complete washing cycle of the machine.

20 Referring now to the supplemental control of the intake of certain washing fluids in accordance with the fluid level within the machine, attention is directed particularly to Figs. 1 and 2. A float chamber 35 is shown as 25 having connection through a pipe 36 with the bottom of the cylinder for receiving fluid therefrom. Located within this float chamber is a float 37 secured at the lower end of a connecting rod 38, which rod connects at its 30 upper end through an adjustable portion 10e with a rock shaft 10d. The upper end of the adjustable rod 10e and the rod 10b are illustrated in detail in Fig. 7 wherein it will be seen for each of the valves 9a, the rock shaft 35 carries an arm for connection with a link 10c which is pivoted at its upper end to a pivotally mounted detent 10b. A corresponding detent 10b is provided in connection with each of the valves 9a, and these detents are adapted 40 to coact with toothed segments 10a to be secured to the handles of such valves. It will be seen, therefore, that upon completion of the circuit including a solenoid 12a, the armature of such solenoid will be raised, there- 45 by operating through the link 11a to raise the handle 10 and actuate the corresponding valve 9a. At this time, the detent 10b will engage the segment 10a and will hold the valve in open position, notwithstanding that 50 the circuit, including this solenoid, might thereafter be deenergized. The release of the detent 10b and accordingly the closing of the valve 9a is governed entirely by the liquid level within the washing machine through 55 the medium of the float 36 and its connecting rod 38. Were it not for the liquid level responsive mechanism, it is apparent that the amount of fluid introduced into the cylinder through any one of the valves 9a during a 60 given period of the opening thereof by the solenoid 12a would depend to a large extent upon the pressure in the fluid supply mains with which the conduits 8 are adapted to be connected. This supplemental control is em- 65 ployed in connection with the valves which

control the supply of water, either hot or cold, inasmuch as the pressure in the water mains is not subject to control and varies in different localities. The supplies of the other washing fluids employed are controllable as to pressure and therefore the solenoid actuated valve mechanism is effective to introduce definite predetermined amounts of such fluids.

I also provide in conjunction with the automatic mechanism above described, a manually operable switch mechanism indicated generally by the reference numeral 40 for selectively actuating the several solenoids and their associated valves. This manual switch mechanism may be employed either in the event of failure of the automatic mechanism or for minor washing operations which do not warrant the building up of the cam cylinder.

25 The end wall 32 of the drum housing 31 is provided with a transparent window 43 through which the corresponding end wall of the rotating cam drum can be seen. In order to visibly indicate the condition of the machine with reference to the cycle of operations which it is performing, I provide the end wall of the cam drum with suitable markings 42 which are adapted to register with an indicating line or other mark 41 provided 35 on the transparent window.

The operation of my improved mechanism is exemplified in Fig. 8 by the placement of the cams 24 on the cam drum 21 for carrying out a washing formula consisting in first introducing cold water for a period of five minutes, opening the outlet valve for a period of two minutes for discharging cold water, simultaneously introducing soap and hot water for a period of fifteen minutes, thereafter again opening the outlet valve for a two minute period to discharge this soap solution, again introducing soap and hot water for a period of fifteen minutes and again thereafter discharging such solution for two minutes, introducing simultaneously a bleach and hot water for five minutes, following this by a second five minute period of introduction of hot water, thereafter opening the discharge valve for a period of two minutes, 100 then introducing sour and hot water for five minutes, again discharging for two minutes, subjecting the material to cold water for five minutes, a two minute discharge period, a five minute period of introduction of both cold water and bluing, and thereafter again opening the discharge valve to drain the cylinder. As indicated herein, cams of a wide variety of sizes corresponding to different time periods may be provided for placement about the periphery of the cam cylinder in the channels 22 thereof. It will be appreciated 105 that a practically unlimited variety of operations are possible by the use of cams of different sizes and by the different placement of 110

115 120 125 130

the cams in the several channels with respect to each other.

The operation of my improved machine is substantially as represented in Fig. 8 except that the period of operation of the three water valves 9a is not determined solely by the size and placement of the cams which control the circuits for the solenoids 12a. As heretofore explained, the supplemental liquid level responsive device is provided in order to compensate for variations in pressure in water mains, and to thereby achieve a definite and unvariable action for any given setting of the mechanism.

- 15 The various circuit connections, including the hand switch mechanism 40, the several cam actuated switch elements 27 and 28, and the several solenoids 12 and 12a will be readily understood from an inspection of Fig. 9. 20 In this figure, the solenoids have been designated by reference characters S' to S⁸ inclusive, and the cam actuated switches as R' to R⁸ inclusive. Following out the circuit of solenoid S⁸, starting from the power line 25 L, it will be seen that the wire M leads to one side of the solenoid S⁸ through a short branch wire N, the other side of this solenoid being connected through wire N', switch R⁸, and line N' to the main line L'. This represents 30 the solenoid circuit including the automatic switch R⁸, and inasmuch as each solenoid is also provided with a manually operable switch X, it may be well to trace out the circuit for the solenoid S⁸ including its manually operable switch. From the lead N' connected to one side of the solenoid, a line O extends to one side of one of the manually operable switches. The other side of this 35 switch connects with a wire P' which is common to one side of each of the manual switches, which wire connects with the wire P which in turn connects to the main line L'. The main line L is connected to the other side of the solenoid through wires M and N. 40 It will be seen that the circuit connections are substantial duplicates for each of the solenoids and switches, a line N connecting the line M to one side of each of the solenoids, and a line N' connecting the other side of 45 each solenoid to one of the cam actuated switches. As to the manually actuated switches, the lines O connect one side of each solenoid with one side of each manual switch, and the common line P' and line P connect the opposite side of each of these switches to the other power line.

The structural details, mode of operation, and advantages of my invention should be readily understood by those skilled in the art in view of the foregoing description. I desire, however, to emphasize certain features of my invention in order to more clearly convey a realization of their merits. First, I would refer particularly to the means whereby variations in pressure in fluid supply

70 mains may be compensated for to the end that operations may be carried out exactly as planned and intended by the different washing formulæ which may be employed. The lack of such a compensating means has heretofore been a very serious matter inasmuch as owing to variations in pressure, the proportions of the different fluids involved in a washing formula might vary to such an extent as to materially affect the quality of the 75 work produced. Such variation might change from day to day as well as being different in different localities and thus render it impossible to produce a uniform quality or class of work over an extended period 80 of time. In the manufacture of machines for distribution through different sections of the country, it is essential that some such means as herein disclosed be provided in order to insure constant operation and results under 85 the varying conditions which are thus encountered.

90 The advantages of my assembled cam drum construction cannot be too strongly stressed in comparison with mechanisms heretofore designed for the same general purpose. As pointed out in describing the structural elements of my invention, the cam drum 21 is removable as a unit by merely swinging the supporting bar 34 laterally 95 about its pivot and then withdrawing the drum endwise from engagement with the shaft 18. A plurality of drums 21 might be suitably built up with the adjustable cams 24 to correspond with the entire range of washing formulæ employed in a given plant. With a complete stock of such assembled drums, it would be but a simple matter to remove one drum and insert another for changing from an operation of one character 100 to a different operation. This structure effects a very considerable saving of time and thus facilitates the carrying out of a variety of operations with the same machine. The cam drum is in effect a "set-up" of a given 105 washing formula and may also serve as a record of the operation of a given machine. It should be appreciated that many changes may be made in the structure and arrangement of the parts shown without departing 110 from the spirit of my invention.

115 What I claim is:

1. In a laundry machine, the combination with a casing, of devices for supplying a plurality of different washing fluids to said casing, a movable member for rendering said devices active and inactive in a predetermined sequence and for determining the active periods of such devices, the duration of such periods being calculated to introduce 120 predetermined volumes of said fluids into said casing, such calculation being based upon normal pressures at the supply sources of said fluids, at least one of said supply sources being subject to pressure variations, and means 125

associated with the corresponding one of said devices for prolonging the active period thereof beyond that determined by said movable member to compensate for subnormal pressures.

2. In a laundry machine, the combination with a casing, of devices for supplying a plurality of different washing fluids to said casing, a movable member for rendering said devices active and inactive in a predetermined sequence and for determining the active periods of such devices, the duration of such periods being calculated to introduce predetermined volumes of said fluids into said casing, such calculation being based upon normal pressures at the supply sources of said fluids, at least one of said supply sources being subject to subnormal pressures, and means associated with the corresponding one of said devices for prolonging the active period thereof beyond that determined by said movable member to compensate for such subnormal pressures, said means being governed by the liquid level in said casing.

25 3. In a laundry machine, the combination with a casing, a plurality of sources of fluid, means placing said casing and sources in communication, valves for controlling the communication between said casing and each of said sources, a movable member for rendering said valves active and inactive and for determining the duration of the active period of said valves, and means responsive to the volume of fluid introduced into said casing for prolonging the active period of certain of said valves.

4. In a laundry machine, the combination with a casing, a plurality of sources of fluid under pressure, means communicating with said sources and with said casing, valves controlling said means, a movable member for opening and permitting the closing of said valves in a predetermined sequence, and means independent of said member for preventing the closing of certain of said valves until a predetermined volume of fluid has been introduced into said casing.

5. In a laundry machine, the combination with a casing, a fluid inlet pipe communicating with said casing, a manifold communicating with said inlet pipe, a plurality of sources of washing fluids, valve controlled passages for placing said sources in communication with said manifold, a movable member for opening and permitting the closing of said valves in a predetermined sequence, and means independent of said member for preventing the closing of certain of said valves until a predetermined volume of fluid has been introduced into said casing.

6. In a laundry machine, the combination with a casing, of devices for supplying a plurality of different washing fluids to said casing, an intermittently rotatable cam carrying

ance with a predetermined washing formula, at least one of said supply sources being subjected to pressure variations, and means associated with the corresponding one of said devices for prolonging the actuation period thereof beyond that determined by said movable member to compensate for subnormal pressures.

In testimony whereof I affix my signature.
